3 Claims

ABSTRACT OF THE DISCLOSURE

6-sulfanilamido-4-methoxypyrimidine (sulfamonomethoxine) is clinically useful for treating malaria, and was found to be effective against both the erythrocytic form (blood form) and the exoerythrocytic form (tissue form) of malaria parasites.

BACKGROUND OF THE INVENTION

(1) Field of the invention

This invention relates to antimalarial compositions comprising 6-sulfanilamido-4-methoxypyrimidine and to a method for treating malaria with such compositions.

(2) Description of the prior art

It has previously been known that some sulfonamides are experimentally effective against malaria parasites but only in a definite stage of their life cycle. However, since the antimalarial effect of these sulfonamides is very uncertain, these drugs have not been employed clinically. Further, high doses or frequent administration of these sulfonamides is necessary in the treatment of malaria. Furthermore, there is a probability of recidivation of the disease when employing such drugs.

Malaria parasites undergo a specific and complicated life cycle. This life cycle is roughly classified into two forms, the exoerythrocytic form (tissue form) and erythrocytic form (blood form). These two forms generally have different sensitivities to chemotherapeutic drugs.

Therefore, no sulfonamides have been known which are perfectly effective against both blood and exoerythrocytic forms. In view of the above, it has not been believed that sulfonamides are worthy of clinical use in the treatment of malaria.

SUMMARY OF THE INVENTION

From extensive investigations, however, applicants have found that 6-sulfanilamido-4-methoxypyrimidine, which was already known as an antibacterial agent (generally called sulfamonomethoxine), surprisingly brought about complete cures of malarial infections both in experimental and clinical use.

DETAILED DESCRIPTION OF THE INVENTION

According to one feature of the invention, said sulfamonomethoxine shows sufficient effectiveness, at relatively low doses, against malaria parasites resistant to antimalarial agents as chloroquine or pamaquine, which have heretofore usually been employed for clinical use.

For example, it has been confirmed by experiments using infected domestic fowls and mice that sulfamonomethoxine is definitely effective against malaria parasites both in the blood and exoerythrocytic stages. Therefore, malaria can be completely cured by several administrations of sulfamonomethoxine.

Sulfamonomethoxine has shown excellent effects with patients suffering from malaria upon oral or intravenous administration of 10–80 mg./kg./day for one to several days, as shown in Example 4. This data was obtained from clinical experiments in the region near the Victoria Lake,

2

which had been famous for multi-occurrences of malaria. Further, prevention of malaria is also effected by administration of said sulfamonomethoxine at dosages of 1–2 g., once a week.

In addition to the above merits, sulfamonomethoxine has previously been clinically employed as a long acting sulfa-drug, as blood levels remain high for quite some time. In this respect, sulfamonomethoxine is an ideal drug for antimalaria treatment.

Sulfamonomethoxine, further, possesses very low toxicity and very stable physical properties. The compound may therefore be easily made into various pharmaceutical formulations, such as injectables, syrups, capsules, tablets or powders by well-known pharmaceutical techniques, employing any pharmaceutically acceptable carrier.

EXAMPLE 1.—PART 1

Plasmodium berghei, which had been collected from infected mice, was inoculated into mice (D.D. strain; 16–19 g. of body weight) intraperitoneally ($2.55\text{--}6.92 \times 10^6$ mg./kg. per mouse). To these mice, various drugs were then orally administered for 7 days, and the infected mice were observed mainly to fall ill and to die. The blood, the liver and the spleen of the mice which survived until the 55th day after the infection were homogenized and inoculated into healthy mice. The existence of parasites was determined by whether or not the inoculated mice also fell ill.

The results are summarized in the following Table 1.

TABLE 1

Drugs	Average daily dose (mg./kg.)	No. of animals tested	Percent protected	Existence of parasites
Pamaquine-----	10	5	0	+
	50	5	0	+
	100	5	0	+
Quinine-----	10	5	0	+
	50	5	0	+
	100	5	0	+
Pyrimethamine-----	2.5	5	40	+
	5	5	80	—
	10	5	100	—
Sulfamonomethoxine-----	10	5	100	—
	50	5	100	—
	100	5	100	—
Infected control-----	-----	5	0	+

PART 2

A comparative examination was made on the antimalarial activity of sulfamonomethoxine with several drugs which are known to be somewhat effective against the parasites. The results are shown in the following Table 2. From the results, it is obvious that the sulfamonomethoxine is the most excellent among all sulfa-drugs with regard to the dosage administered compared with the effectiveness of treatment.

TABLE 2

Drugs	Average daily dose (mg./kg.)	No. of animals tested	Percent protected	Existence of parasites
Sulfamonomethoxine-----	2.5	5	80	±
	5	5	100	—

3
EXAMPLE 2

When chicks are infected with *Plasmodium juxtanucleare*, the number of the parasites reaches a maximum at 10 days in erythrocytic stages and at 3-4 weeks in exoerythrocytic stages. Based on the above, the examinations of the activity of sulfamonomethoxine against the parasites both in exoerythrocytic and erythrocytic stages were performed.

Materials and method

Twenty one-day-old chicks were used as one group.

5 A blood infected with *Plasmodium gallinaceum* was injected into eleven-day-old chicks (1.4×10^7 mg./kg. per chick) intramuscularly. Each drug, mixed with diet, was administered for 7 days after the infection. Determinations on the effect of the treatment were made by the presence or absence of erythrocyte with parasites after inoculation and by the survival ratio of the chicks at the 40th day after the inoculation.

10 The results are summarized in the following Table 5.

TABLE 5

Drug	Daily dose (mg./kg.)	After the inoculation				Survival ratio at 40 days after inoculation, percent
		8 days	11 days	14 days	30 days	
Sulfamonomethoxine-----	2	—	—	—	—	100
	5	—	—	—	—	100
	10	—	—	—	—	100
Pyrimethamine-----	1	—	—	+	++	55
	15	—	—	—	+	85
Plasmochin-----	1	—	—	+	++	95
	5	—	—	—	++	95
Infected control-----	—	—	+	+++	—	0

EXAMPLE 4

Blood infected with *Plasmodium juxtanucleare* was inoculated into the chicks by intracardiac injection. The drug administration was started from the 8th day after inoculation for the examination in the erythrocytic stage, and from the 17th day after inoculation in the exoerythrocytic stage, for 5 days respectively.

Determinations of the effect of treatment were made by 30 calculation of the rate of erythrocytes within which

30 the parasites lived to the total erythrocytes and by mortality of the chicks.

35 The results are summarized in the following Table 6.

TABLE 6

Number	Drugs and dosages	Number of patients	Average	Average	Percent cured
			days to clear parasitemia	days to clear clinically	
1-----	SMM 2 g. (i.v.) plus SMM 1 g. (p.o.) in single dose.	23	2.2	4.1	100
2-----	SMM 2 g. (i.v.) then 0.5 g. daily for 3 days.	20	2.4	3.7	100
3-----	SMM 2 g. (p.o.) then 0.5 g. daily for 2 days.	46	2.5	4.3	100
4-----	SMM 2 g. (p.o.) in single dose.	47	2.7	4.2	100

parasites lived to the total erythrocytes and by mortality of the chicks.

The results are summarized in the following Tables 3 and 4.

EXAMPLE 5

Preparation of 500 mg. tablets
One thousand tablets for oral use, each containing 500

TABLE 3.—RESULTS IN ERYTHROCYTIC STAGE

Drug	Average daily dose (mg./kg.)	(Erythrocytes with parasites) Total erythrocytes observed			Mortality, percent	
		Before administration				
		5 days	15 days	30 days		
Sulfamonomethoxine---	50	0.6	—(0)	—(0)	—(0)	
	10	0.6	—(0)	—(0)	—(0)	
Infected control-----	—	0.6	+	+	+	
					45	

TABLE 4.—RESULTS IN EXOERYTHROCYTIC STAGE

Drug	Average daily dose (mg./kg.)	(Erythrocytes with parasites) Total erythrocytes observed			Mortality, percent	
		Before administration				
		5 days	15 days	30 days		
Sulfamonomethoxine---	50	1.4	—(0)	—(0)	—(0)	
	10	1.3	—(0)	—(0)	—(0)	
Infected control-----	—	1.1	+	+	+	
					65	

mg. of sulfamonomethoxine, were prepared from the following materials:

	G.
Sulfamonomethoxine -----	500
Corn starch -----	40
Magnesium stearate -----	9.4

The above ingredients were thoroughly mixed and compressed into tablets, each tablet containing 500 mg. of sulfamonomethoxine according to conventional methods.

EXAMPLE 6

Preparation of a 10% (w./v.) injectable solution

A solution was prepared from the following ingredients:

Sulfamonomethoxine—300 g.	15
Sodium hydroxide—42 g.	
Distilled water for injection—3 liters	

The solution containing the above ingredients were filtered and filled into ampoules, then sterilized.

What is claimed is:

1. A method for treating malaria which comprises orally or parenterally administering to a patient infected with malaria, 6-sulfanilamido-4-methoxy pyrimidine in an antimalarially effective dose.

2. The method of claim 1, wherein the antimalarially effective dose is a range of from 10 mg. to 80 mg. per kg. of body weight per day.

3. The method of claim 1, further comprising in combination with said 6-sulfanilamido-4-methoxy pyrimidine, 10 a pharmaceutically acceptable carrier.
